COOKING APPARATUS

Norman J. Peters, Fond du Lac, Wis., assignor to
 Damrow Brothers Company, Fond du Lac, Wis.,
 a corporation of Wisconsin

Application July 22, 1946, Serial No. 685,460

1 Claim. (Cl. 220—15)

1

The invention relates to cooking apparatus and more particularly to cookers for cooking various material by either the continuous or batch process and in which the material being treated is agitated during the cooking process.

The general object of the invention is to provide a cooker in which live steam may be introduced into the cooking chamber and a steam jacket surrounds the cooking chamber, and while the apparatus shown is particularly adaptable to the making of process cheese, it may be used for other cooking purposes. In such an apparatus problems of reinforcing the jacket space, anchoring the direct injection steam pipes, supporting the feed screw or screws and permitting of their ready removal, and securely clamping the top cover are present. Among the several features of the invention is a reinforcement for the lining and jacket comprising a stay bolt connection therebetween which allows freedom of movement between the lining and jacket when the rate of thermal expansion is not the same or when stresses occur in either.

Another feature of the invention is the anchoring of direct steam injection pipes to the lining at an angle to the cooker centerline and also at an angle to horizontal to assist in the movement of the material being treated and the connection of these pipes to the jacket by a flexible mounting.

Another feature of the invention is the mounting of the feed screw on a half sleeve bearing at one end and a bearing unit at the other end disposed outside the cooking area.

Another feature is the structure permitting removal of the feed screw without disturbing the exteriorly located bearing and packing gland by a detachable coupling which also forms a section of the screw, with leakage around the shaft prevented by means of said packing gland.

Another feature of the invention is the means for clamping a removable cover in pressure-tight relation with the lining and so that the cover may be mounted to swing from either side of the apparatus to meet installation conditions, it being noted that the sealing pressure is applied in the areas where the sealing surfaces are located and not on those parts of the cover where distortion might take place.

The invention consists in the above and other features hereinafter described and more particularly defined by claim at the conclusion hereof.

In the drawings:

Fig. 1 is a side elevation view of a cooking ap-

paratus embodying the invention, parts being broken away and parts being shown in section;

Fig. 2 is a horizontal sectional view taken on the line 2—2 of Fig. 1;

5 Fig. 3 is an enlarged detailed vertical sectional view taken on the line 3—3 of Fig. 1;

Fig. 4 is an enlarged side elevation view of a portion of the apparatus, parts being broken away and parts being shown in section;

10 Fig. 5 is a view similar to Fig. 4 showing another portion of the apparatus;

Fig. 6 is an enlarged front end elevation view of the apparatus, parts being broken away;

15 Fig. 7 is an enlarged detailed side elevation view showing one of the pipe mountings, parts being broken away;

Fig. 8 is a detailed sectional view taken on the line 8—8 of Fig. 3;

20 Fig. 9 is a vertical sectional view through an apparatus showing certain modifications.

Referring to the drawings, the numeral 10 designates a frame in which the cooker and its drive mechanism are mounted. The cooker includes an outer jacket 11 formed of suitable sheet metal, such as stainless steel, with flanged tops 12 extending along its sides and a rounded bottom 13, this shell being connected, as by welding, at its ends to end plates 14 and 15, the end plate 15 having an opening 16 therein and being provided with spaced guides 17 for the mounting of a slideable valve plate 18 provided with a handle 19 and having an outlet opening 20 therein to align with opening 16. The lining is formed by a trough-like shell 21 of

30 sheet metal, such as stainless steel, having side flanges 22 welded or otherwise suitably secured to the flanges 12 of the jacket shell and having either a single curved bottom in the case of a single screw, as shown in Figs. 1 to 3, or a double curved bottom, as shown in Fig. 9, in the case of a double feed screw, said lining being connected by welding to the end plates 14 and 15. The members forming parts of the frame 10 are welded or otherwise suitably secured either to the flanged portions of the jacket and lining or

40 to the sides of the jacket. The jacket and lining or liner are reinforced by a plurality of stay bolt connections, one of which is shown in detail in Fig. 8 and comprises a plate 23 welded or otherwise fixedly secured to the outer side of the lining and carrying a U-shaped rod 24 whose transverse portion is slidably mounted in an opening 25 of a bolt 26 whose threaded shank 27 extends through the jacket and is held in

50 tensioned engagement therewith by a washer 28

and nut 29 which parts are then welded together and to the outer surface of the jacket as indicated in Fig. 8. This type of reinforcing spacing means between the jackets allows free movement between the lining and the jacket when the rate of thermal expansion is not the same and/or when stresses occur in either.

Live steam is introduced into the lining through steam pipes 30, each of which projects downwardly at an angle to the center line of the cooker and forwardly at an angle to the horizontal, as shown in Figs. 2, 3 and 7, so that the steam issues in a direction downwardly and toward the exit end of the machine which acts to assist in imparting a movement to the material being treated and in a general direction toward the exit end of the machine. The inner ends of the pipes are welded to the lining, and they project through enlarged openings 31 in the jacket or outer shell and carry or are welded to flexible metal disks or plates 32 whose peripheral portion 33 is welded to the outer side of the jacket so as to provide a flexible mounting and allow movement between the lining and the jacket when the rate of thermal expansion is not the same and/or when stresses occur in either. Each of the live steam pipes 30 connects up with a steam supply header 35 through union couplings and branch pipe connections 36, each branch being provided with a shut off valve 37. For heating the space between the jacket and the lining a steam pipe 38 connects through branches 39 with the interior of the jacket and a similar return connection 40 is provided. The jacket steam is controlled through any suitable valve, not shown.

The cooker may be provided with one or more rotatable feed screws of the spiral flight type 41. The forward end of each feed screw is journalled in a half bearing 42 carried by the rear plate 15. The front end of the feed screw has a shaft portion 43 which carries a coupling 44 having a screw flight 46 formed as a part thereof. This coupling is slidably mounted on the shaft 43, but may be secured in driving relation therewith by a taper pin 47 and is likewise secured to a projecting end 48 of a driven shaft by a taper pin 49, as shown in Fig. 4. The shaft 48 is supported by bearings located in a bearing support 50 mounted on frame 10. Leakage around the shaft is prevented by a packing gland 51 and sleeves 52 clamped against the gland 51 by bolts 53. Also as the packing gland 51 and the bearing support 50 are located outside of the cooking chamber, they can be kept cool, clean, and do not have to be disturbed in the removal of the feed screw. The shaft 48 in the case of a single screw is driven from an electric motor 54 connected to a gear reduction 55 whose shaft 56 is connected by a chain and sprocket drive 57 with the shaft 48. Where two feed screws are used, one of the screws is driven as just described and the other has an intermeshing geared connection (not shown) with the shaft 48 but of known construction.

With the above arrangement removal of the pins 47 and 49 permits the coupling 44 to be slipped forwardly along the shaft 43 so as to disengage it from the shaft 48 and thus permit the whole screw shaft 41 to be lifted up out of the lining.

The front end of the cooking chamber is covered by a feed hopper 58, and the remainder of the top of the cooking chamber is covered by the sheet metal cover 59 whose central portion at spaced intervals is provided with upwardly projecting studs 60 carrying nuts 61 by which cover

frame members 62 are clamped to the top of the cover. The cover frame members at one end 62' extend down to provide an apertured ear adapted for mounting between spaced hinge ears 63, on either side of the apparatus, these parts being secured together by a hinge pin 64. The ears 63 are provided with threaded shanks 65 that protrude through holes in the flanges 12 and 22 and a flanged bracket 67 secured to the outer side of the jacket. The ear is clamped to the above named flanges by means of a nut 66 or other suitable means. The cover frame members 62 have cover clamping screws 68 adjustably mounted therein and engaging the cover at spaced points over the flanged sides 12 and 22 of the lining and jacket. These screws 68 are held in pressure engagement with the cover by a series of cover clamps, each comprising a bolt 69 hingedly connected by the pin 70 to the opposite set of ears 63 from that for the cover frame members 62 and adapted to be swung up between the forked end 71 of said member 62 and be clamped to said member 62 in this position by a nut 72 engaging a washer 73 and provided with a hand crank extension 74. As noted above, the apertured ends of the frame members 62 and the bolts 69 are interchangeable with either set of ears 63, so that the cover may be mounted to swing upwardly toward the right, as shown in Fig. 3, or by turning the arms 62 through one hundred eighty degrees the cover may be mounted to swing upwardly to the left, as viewed in Fig. 3, it being noted that the studs 61 are centrally disposed relative to the screws 68 and the ears 63 on opposite sides of the apparatus.

The general operation of the structure above described is similar to other cookers of this general type. The valve 18 is closed for batch type cooking and is opened for continuous process cooking, the screw or screws 41 serving to keep the material agitated during the cooking process. Where one screw 41 is used, its flight and rotation are preferably arranged to produce a feeding tendency of the material along the bottom of the trough or lining from the inlet to the outlet end. With the double screw feed, one screw is right handed and one left handed, but as the direction of rotation is opposite on the two screws, the material is carried forward by both screws. The double screw feed provides a more efficient mixing than the single screw.

I desire it to be understood that this invention is not to be limited to any particular form or arrangement of parts except in so far as such limitations are included in the claim.

What I claim as my invention is:

In a cooking apparatus, the combination of a lining and a jacket joined together at their upper side portions and spaced apart at their sides and bottoms to form a jacket space, a bolt extending through said jacket and into said jacket space and having transverse opening in the portion within said jacket space, and a U-shaped rod having a transverse portion of greater length than the transverse opening in said bolt and slidably extending therethrough and secured at its ends to said lining to form a lengthwise movable anchorage connection between said bolts and said lining.
